UNITED STATES PATENT OFFICE.

CHARLES WM. MANKER, OF NEBRASKA CITY, NEBRASKA, AND GEORGE F. MANKER, OF BEDFORD, IOWA, ASSIGNORS OF ONE-THIRD TO HENRY E. MANKER, OF ELLIOTT, IOWA.

GALVANIC APPARATUS FOR DENTAL SURGERY.

SPECIFICATION forming part of Letters Patent No. 423,616, dated March 18, 1890.

Application filed August 23, 1889. Serial No. 321,752. (No model.)

To all whom it may concern:

Be it known that we, CHARLES WILLIAM MANKER, of Nebraska City, in the county of Otoe and State of Nebraska, and GEORGE F. MANKER, of Bedford, in the county of Taylor and State of Iowa, have invented a new and Improved Apparatus for Use in Dental Surgery, of which the following is a full, clear, and exact description, reference being had to the accompanying drawing, which is a plan view, partly in section, of our improved galvanic apparatus.

The object of our invention is to construct a simple and effective galvanic apparatus for use in connection with the forceps in the extraction of teeth or other dental operations, the said apparatus being designed to reduce the pain of the operation and treatment of oral diseases.

Our invention consists in the combination, with a battery and induction-coil, of an interrupter operated by two electro-magnets and provided with two sets of contact-points.

It also consists in an adjustable interrupter-armature arranged to vary the speed of the breaks in the primary circuit.

The invention also further consists in the combination, with the electrodes running from the secondary wire of the induction-coil, of rings adapted to be worn upon the fingers of the operator, either one or two fingers, as desired, for forming an electric contact with the forceps, all as will be hereinafter more fully described.

Upon a suitable base A is mounted an induction-coil B, provided with a soft-iron core *a* in the usual way. To the said core is fitted a sliding shield C, of brass or other non-magnetic material, by means of which the strength

of the secondary current may be varied. The primary wire of the induction-coil is branched and connected with two magnets D D', and the said magnets are connected with the posts E E', carrying contact-screws *b*. The mag-

nets D D' are connected up in a diagonally-opposite arrangement with the posts E E'. Between the contact-screws *b* is supported an armature-spring *c* by the post *d*, the said post being slotted to receive the spring and pro-

vided with a clamping-screw *e* for holding the spring *c* in any desired position. To the free end of the armature-spring *c* is secured an armature *f*, which is within the field of the polar extremities *g g'* of the magnets D D'. The post *d* is connected by a wire *h* with a binding-post *i*, and the said binding-post is connected with one pole of the battery F, the remaining pole of the battery being connected with the binding-post *i'*, and the said binding-post *i'* is connected with the remaining terminal of the primary coil.

The terminals of the secondary-coil are connected with the binding-posts *j j'*, and to the base A are secured the binding-posts *k k'*, which are connected electrically. The conductors *l l'* are connected with the binding-posts *k' j'* and with the electrodes *m m'*, which are to be held by the hands of the patient. The conductors *n n'* are connected with the binding-posts *j k*, also with rings *o o'*, or other means, which are to be worn upon the fingers of the hand of the operator.

When the vibrating armature *f* is in operation, the electric contact is made and broken in the circuits of the magnets D D' in alternation, thereby sending rapid electrical impulses to the primary wire of the induction-coil B and inducing in the secondary wire pulsations of much higher intensity. The secondary current passes through the hands of the patient, through rings on the hand of the operator, and the forceps in contact with the said rings to the patient's teeth. These rings may be used for making and breaking the secondary circuit. The secondary current applied in the manner indicated relieves the pain of extraction.

The strength of current may be varied by moving the shield C in or out over the core *a*, and the rapidity of the vibrations of the armature and its spring may be varied by changing the adjustment of the armature-spring in the post *d*.

Having thus described our invention, we claim as new and desire to secure by Letters Patent—

1. The combination of the magnets D D', the adjustable armature-spring *c* and arma-

ture f , carried thereby, the contact-screws b , and the electrical connections, substantially as specified.

2. The combination of the induction-coil B , the magnets $D D'$, connected in branch circuits, the armature-spring c , carrying the armature f , the contact-screws b , and the electrical connections, substantially as specified.

3. The combination, with the induction-coil B , of the conductors $n l'$, connected with the terminals of the secondary wire, and the conductors $n' l$, connected electrically, the said

conductors $l l'$ being provided with electrodes $m m'$ and the conductors $n n'$ being provided with the electrodes $o o'$, substantially as specified, which may be worn on separate fingers or on one finger of the operator, as desired.

CHAS. WM. MANKER.
GEORGE F. MANKER.
